UNITED STATES PATENT OFFICE.

EDWARD WILLIAM BRYANT, OF NEW YORK, N. Y., ASSIGNOR OF ONE-HALF TO JOHN J. CORELL, OF NORFOLK, VIRGINIA.

SYSTEM OF SHELF-SUPPORTS.

No. 873,496.

Specification of Letters Patent.

Patented Dec. 10, 1907.

Application filed November 22, 1905. Serial No. 288,541.

To all whom it may concern:

Be it known that I, EDWARD WILLIAM BRYANT, a citizen of the United States, residing in the city of New York, in the county 5 and State of New York, have invented a new and Improved System of Shelf-Supports, of which the following is a specification.

My invention relates to supports for shelves in libraries, stores or other locations, and the 10 object of my improvements is to provide a system of shelf supports which can be readily set up in any desired location, and adapted to spaces of different size, which can be extended so as to provide supports for additional shelving, as required, and which will be, when set up, a homogeneous and practically solid structure.

In carrying my invention into effect, I form a skeleton structure, built up of shelf 20 supporting parts or frames, which carry the shelf brackets, and are arranged in a series of aligned stacks. The frames composing each stack are superposed one upon another, and suitably secured from both vertical and horizontal movement. The stacks of frames are 25 held together by connecting pieces, and the entire structure, while built up of independent separable parts, is locked together throughout, and forms a rigid, homogeneous 30 whole, which, while readily put together, can be taken apart only by removing the parts in the inverse order of their putting together. The connecting pieces between the stacks 35 may be located at the ends of the shelf supporting frames when a single line of shelving is desired, or at the centers of the shelf supporting frames when it is desired to have a double line of shelving.

My invention will be best understood by 40 reference to the accompanying drawings, in which it is illustrated in concrete form.

Corresponding parts are indicated by the same letters of reference in the different figures.

45 Referring to the drawings, Figure 1 shows an elevation of two stacks of shelf supporting frames, each consisting of two of such frames with the connecting pieces, seen from the rear. Fig. 2 shows a vertical section of two 50 shelf supporting frames, with a connecting piece. Fig. 3 is a plan view of two shelf supporting frames, seen from above, with a connecting piece. Fig. 4 is a side view of one of the shelf supporting frames. Figs. 5 and 6 55 show details of construction. Fig. 7 is a

plan view showing the arrangement of parts where the connecting pieces are located at the centers of the stacks, to form a double line of shelves, and also an arrangement for supporting small triangular shelves at the 60 ends of such double shelf racks. Such double shelf racks are used when it is desired to have shelves standing out from a wall, or independent, as in library alcoves. Fig. 8 is a detail sectional view showing the 65 manner in which the connecting frames engage the interlocking portions of the side or end frames and prevent the disengagement thereof. Fig. 9 shows a method of connecting a section of shelving at right angles with 70 other shelves; and Fig. 10 shows in section a clip which may be used for supporting the inner ends of such shelves.

All the parts are preferably made of iron, or other suitable metal, cast, or otherwise 75 formed, in the proper shape.

Referring to the drawings, A, B, indicate two of the shelf supporting parts of which the shelf supporting stacks are built up. These are preferably made, as shown, in the 80 form of skeleton frames, consisting of separated relatively thin vertical supports, O, O, which are connected at top and bottom by horizontal parts, provided at top and bottom with horizontal flanges or projections, h, h, 85 adapted to receive and rest upon the corresponding flanges or projections respectively of the frames immediately above and below. Along the top of each frame runs a tongue or tenon, a, preferably extending the entire 90 length of the frame, and of such shape that it is undisengageable vertically from a groove of corresponding shape, and along the lower face of each runs a groove, b, adapted to receive the tongue or tenon of the frame below. Secured to the uprights, O, O, are 95 ledges or brackets, s, s, upon which the shelves rest when in position. These may be made integral with the frames, or be detachably secured thereto in any usual or well known manner. They project sufficiently 100 beyond the relatively thin vertical parts, O, O, of the frames to form a secure support for the shelves, which may be readily slipped into place as the structure is built up, or 105 after it is completed.

C indicates one of the connecting pieces by means of which the stacks of shelf supports are held together. These are provided at each end with two dove-tailed ears, c, c, 110

which are adapted to engage with correspondingly shaped slots or sockets, *d*, *d*, in the shelf supporting frames, *A*, *B*. The stacks of shelf supporting frames preferably 5 rest upon base pieces, *D*, which may, if desired, be rigidly secured to the floor. The upper surfaces of these base pieces are provided with tenons, *a*, in the same manner as the upper surfaces of the frames, *A*, *B*.

10 In setting up a system of shelf supports, two of the shelf supporting frames, as *A*, *B*, are placed upon two base pieces, *D*, by sliding the grooves *b*, upon the tenons, *a*, on the upper surfaces of the bases. A connecting 15 piece, *C*, is then put in position between the frames, *A*, *B*, the ears, *c*, *c*, being placed in the slots, *d*, *d*, in the upper and lower rails of the frames. The flaring ends of a stretcher rod, *E*, are placed in slots, *e*, *e*, in the lower 20 rails of the frames, in order to prevent any lateral displacement of the fronts thereof. A second pair of shelf supporting frames, *A'*, *B'*, are then placed upon those already in position, by sliding the grooves, *b*, upon the 25 tenons, *a*, until the slots, *d*, *d*, in their lower rails register with the corresponding slots in the upper rails of the frames, *A*, *B*, and a second connecting piece, *C'*, and a stretcher rod, are put in place between these in the 30 same manner as before. In this way the stacks of shelf supporting frames are built up, until the structure is of the desired height. The slots, *d*, *d*, in the upper rails of the frames extend somewhat into the tenons, 35 *a*, *a*, and the corresponding slots in the lower rails extend into the grooves, *b*, *b*, the slots of the superposed frames registering one with another, so that when a connecting piece, as *C'*, is put in place, its lower ears, *c*, *c*, engage 40 at the same time the upper rails of the frames, *A*, *B*, and the lower rails of the frames, *A'*, *B'*, and so on throughout the structure. Thus each frame is interlocked 45 with the one upon which it rests, and is immovable thereon. Each stack of shelf supporting frames is also joined to the adjacent stack by the connecting pieces, and the result is a structure which, while easily put together, is homogeneous and rigid, and can be 50 taken apart only by removing the pieces in the inverse order of their putting together. In further extending the structure laterally, a third stack of shelf supporting frames is built up in the same manner as already de- 55 scribed, and joined to one of those already in place by connecting pieces, in the same way.

When it is desired to have double stacks of shelves extending out from a wall to form alcoves, as in libraries, double shelf support- 60 ing frames, shown at *G*, Fig. 7, may be em- ployed. In these the slots, *d*, for receiving the ears, *c*, of the connecting pieces, *C*, are located at the center of the frames. Such an arrangement is equivalent to two stacks of 65 single shelf supporting frames placed back to

back. Small triangular shelves may be located at the ends of such stacks, by means of frames, *H*, Fig. 7, located at right angles to the double frames, *G*, and connected therewith by stretcher rods, *F*, *F*. Such end 70 frames mortise, but do not lock to those below them.

A modified arrangement for locating shelves at right angles to other shelves is shown in Fig. 9. In this arrangement the outer ends of the 75 frames, as *A*, are provided with slots, *d'*, to receive the ears, *c*, of connecting pieces, *C''*, the ears on the outer end of which engage the slots in frames *A''*, placed at right angles to the frames, *A*. The frames, *A''* may be 80 either single, as shown in Fig. 9, or double, as shown in Fig. 7. The outer end of the shelf, *S'*, is supported on the frame, *A''*, in the manner already described, while its inner end is secured to the shelf, *S*, in any suitable 85 manner, as by clips, *f*, shown in section in Fig. 10. Such an arrangement is employed in turning a line of shelves, as at the corner of a room, or for connecting alcoves with a series 90 of wall shelving. The shelves may be placed in the structure after it is completed, or as it is built up, and can be removed at any time. Ornamental fronts or moldings may be secured to the structure at top and bottom, 95 if desired, in any usual or convenient manner.

My above described invention enables the construction of a light, metal, fireproof shelf-supporting structure, which is economical to manufacture, which can be easily and quickly 100 put in place, which is adaptable to spaces of any size, and which can be extended either horizontally or vertically, or both, as may be required, to meet the needs of the user.

While I have described the best means at 105 present known to me of carrying my invention into effect, it will be evident that various modifications, which will readily occur to those skilled in the art, may be made in the details of construction, as, for example, in 110 the manner of securing the superposed frames to one another, and of securing the connecting pieces to the stacks of frames, without departing from the spirit of my invention; and I do not wish to be understood 115 as limiting myself in these respects.

What I do claim as new, and desire to secure by Letters Patent, is:

1. A skeleton shelf supporting structure, consisting of a series of aligned stacks of 120 superposed shelf supporting frames, provided upon their upper and lower surfaces respectively with dovetailed tongues and grooves, and upon their sides with registering dovetailed slots, and connecting pieces be- 125 tween said stacks, provided with dovetailed ears adapted to enter said slots, and so arranged that each of said connecting pieces engages at each end with two of said shelf supporting frames. 130

2. A skeleton shelf supporting structure, composed of a series of aligned stacks of shelf supporting frames, provided upon their upper and lower surfaces with dovetailed 5 tongues and grooves, whereby vertical displacement of said frames is prevented, and connecting pieces between said stacks so arranged that each of said pieces engages at each end with two of said shelf supporting 10 frames.

3. A skeleton shelf supporting structure, composed of a series of aligned stacks of shelf supporting frames, provided upon their sides with registering dovetailed slots, and connecting 15 pieces between said stacks, provided at each end with dovetailed ears adapted to enter said slots, and so arranged that each of said connecting pieces engages at each end with two of said frames, whereby the stacks 20 are held together, and horizontal displacement of said frames is prevented.

4. A skeleton shelf supporting structure, composed of a series of aligned stacks of shelf supporting frames, means for preventing 25 vertical displacement of said frames, and connecting pieces between said stacks, so arranged that each of said connecting pieces engages at each end with two of said shelf supporting frames, whereby the stacks are 30 held together, and horizontal movement of said frames one upon another is prevented.

5. A skeleton shelf supporting structure composed of aligned stacks of vertical frames, having interlocking devices for preventing 35 the vertical displacement of said frames and provided with shelf supports, and connecting pieces independent of the shelving constructed to hold the stacks together, and prevent the disengagement of said interlocking 40 parts, substantially as described.

6. A skeleton shelf supporting structure, composed of a series of aligned stacks of separable vertically disposed frames, having interlocking devices for preventing the vertical 45 displacement of said frames, and provided with shelf supports, and means independent of the shelving for holding said stacks together, substantially as described.

7. A skeleton shelf supporting structure 50 composed of a series of aligned stacks of separable vertically disposed frames, each of which is provided at its upper and lower ends with devices adapted to interlock with other similar frames, to prevent their vertical displacement, each of said frames being also provided with horizontal shelf supporting 55 projections, and connecting pieces, independent of the shelving, extending between said stacks, substantially as described.

60 8. In a skeleton shelf supporting structure, the combination of a shelf supporting frame consisting of vertical supporting parts and horizontal connections between such parts, and carrying shelf supporting brackets, and 65 means for securing such frames to other

similar frames disposed both vertically and horizontally in relation thereto.

9. A shelf supporting frame adapted to form part of a skeleton shelf supporting structure, and comprising vertical supports 70 and shelf brackets carried thereby, horizontal connections between such supports, flanges projecting horizontally beyond the plane of said supports, and on the top and bottom thereof, respectively, a dovetailed tongue 75 and groove adapted to engage similar tongues and grooves of other frames.

10. A shelf supporting frame adapted to form part of a shelf supporting structure, having horizontal top and bottom pieces, 80 provided with interlocking portions, for engaging parts above and below said frame, and separated vertical supports relatively thinner than the top and bottom pieces, and provided with shelf supporting brackets, sub- 85 stantially as described.

11. A shelf supporting frame adapted to form part of a shelf supporting structure, having horizontal top and bottom pieces, 90 provided with interlocking portions, for engaging parts above and below said frame, and separated vertical supports relatively thinner than the top and bottom pieces, and provided with shelf supporting brackets having portions extending laterally beyond 95 said supports, substantially as described.

12. An integral shelf supporting frame adapted to form part of a shelf supporting structure, comprising flat horizontal top and bottom pieces provided, the one with projecting portions and the other with recessed portions for engaging other parts of the structure above and below said frame, vertical supports connecting said top and bottom pieces adjacent to their ends, and being 100 relatively thinner than said top and bottom pieces, and shelf supporting brackets extending from one of said vertical supports to the other, between the top and bottom pieces, and having portions extending laterally beyond 110 the vertical plane of said vertical supports, substantially as described.

13. In a skeleton shelf supporting structure, the combination with vertically disposed side frames, provided at top and bottom with interlocking devices for engaging parts of the structure above and below the same, and having shelf supporting brackets, of a vertically disposed connecting piece, provided at each end with interlocking portions adjacent to the top and bottom of the same, and engaging said side frames centrally, for spacing said side frames and holding them in vertical position, said shelf supporting brackets extending on both sides of 120 125 said connecting piece, substantially as described.

14. In a system of shelf supports consisting of shelf supporting frames and connecting pieces between said frames, as a means of 130

changing the direction of a line of shelves, the combination with a shelf supporting frame of a connecting piece engaging with the end of such frame, and a second shelf supporting frame engaged with such connecting piece, and standing at right angles to said first mentioned frame.

15. A skeleton shelf supporting structure comprising vertically disposed supporting frames, each provided at top and bottom with interlocking devices, for preventing the vertical disengagement of said frames, and provided with shelf supporting portions, and horizontal connecting pieces, independent of 10 the shelves engaging said vertical frames, and having portions for locking said frames against horizontal displacement, with respect to each other, substantially as described.
16. A skeleton shelf supporting structure comprising vertically disposed supporting side frames, provided at top and bottom with interlocking devices for engaging similar frames above and below the same, and provided with shelf supports, and a vertically disposed connecting frame, provided at each 15 20 25

end with interlocking devices adjacent to the top and bottom thereof for engaging interlocking parts of said side frames, for spacing them and holding them in vertical position, 30 substantially as described.

17. A skeleton shelf supporting structure, comprising vertically disposed supporting side frames, provided at top and bottom with interlocking devices for engaging similar frames above and below the same, and having horizontal shelf supports, a vertically disposed connecting frame, provided at each end with interlocking devices adjacent to the top and bottom, to engage the side frames 40 adjacent to one end of the same, and a stretcher rod, provided with interlocking parts at each end for connecting the opposite edges of said side frames, substantially as described. 45

In testimony whereof, I have hereunto subscribed my name, this 14th day of November A. D., 1905.

EDWARD WILLIAM BRYANT.
